UNITED STATES PATENT OFFICE

NORMAN LEW WARFORD, OF RAHWAY, NEW JERSEY

DESIGN FOR A GAME BOARD

Application filed October 2, 1930. Serial No. 37,109. Term of patent 7 years.

To all whom it may concern:

Be it known that I, NORMAN L. WARFORD, a citizen of the United States, residing at Rahway, in the county of Union and State of New Jersey, have invented a new, original, and ornamental Design for Game Board, of which the following is a specification, reference being had to the accompanying drawing, forming a part thereof.

The figure is a plan view of a game board showing my new design.

The game board has no appreciable thickness.

I claim:

The ornamental design for a game board as shown and described.

NORMAN LEW WARFORD.
